SELF-LUMINOUS DEVICE

Joseph A. Kelly, New York, N. Y., assignor to
Radium Dial Company, New York, N. Y., a
corporation of Delaware

Application March 29, 1932. Serial No. 601,757

1 Claim. (Cl. 240—2.25)

This invention relates to self-luminous devices, and with particularity to radium luminous markers for pendants or the like.

An object of the invention is to provide a self-luminous terminal for a chain, cord or other similar object.

Another object is to provide a pull chain or cord with a self-luminous terminal marker of improved shape and construction.

10 A feature of the invention resides in a draw or pull chain, cord or similar article having a self-luminous terminal or marker, in conjunction with a novel form of light transparent housing for said terminal.

15 A further feature of the invention resides in a terminal for a lamp chain, cord or similar article which is designed so as to facilitate its location in the dark.

Other features and advantages not specifically 20 enumerated will be apparent after a consideration of the following detail descriptions and the appended claim.

While the invention will be described herein-after as applied to a chain such as ordinarily 25 used on electric lamps or the like, it will be understood that the invention is not limited thereto, but is capable of application in any situation where a luminous terminal is required.

Accordingly in the drawing, 30 Fig. 1 represents a draw or pull chain having a self-luminous terminal according to the invention;

Fig. 1^a represents a slight modification of the structure of Fig. 1;

35 Fig. 2 represents a modified form of the terminal of Fig. 1;

Figs. 3 and 4 represent still further modifications of the luminous terminal; and

Fig. 5 shows a still further modification of the 40 invention.

Referring to Fig. 1, the numeral 1 represents any conventional type of chain or cord such as is ordinarily employed on electric lamps for switching the current on and off. It will be understood 45 however that the invention is not limited to the particular type of chain disclosed. The chain as shown comprises a series of ball-like links 2 which terminate at the upper end in a coupling member 3 having an opening 4 adapted to fit over a chain

50 similar to the chain 2. The chain 1 terminates at its lower end in an enlarged member 5, preferably of ball-like construction although the invention is not limited in this respect to any particular shape for the member 5. However, it is found that when the member 5 is made spherical

that the greatest efficiency for self-luminous purposes is achieved. Furthermore, the member 5 may be the ordinary ball terminal of an electric light chain, or if desired it may take the form of a separate body or spherical member attached in any convenient manner to the lower end of the chain 1. The member 5 is provided with a coating 6 of self-luminous material, preferably radium luminescent paint or the like.

It has been found that this radium luminescent material has its greatest efficiency as a self-luminous coating when it is not covered by any light absorption covering. Consequently, it is preferred to apply the radium luminescent coating to the member 5 so that the said coating is exposed, without any superposed layers of protective coating, although if desired a very thin protective coating of a transparent varnish may be employed. In order to protect the coating 6, and at the same time provide a terminal which can be very readily grasped, there is provided a hollow housing 7 of glass or other transparent material such as celluloid or the like. While Fig. 1 shows the member 7 bell shaped, it will be understood that the invention is not limited in this respect to any particular shape, but is capable of various modifications some of which are illustrated in Figs. 2, 3 and 4. The member 7 is provided at its upper end with a small opening 8 to receive the chain 1. If desired, reliance may be placed upon the member 5 to support the weight of the member 7. On the other hand, if desired the member 7 may be supported by the chain 1 proper, in any convenient manner, as by deforming a pair of the chain links 2 between which the member 7 is to be supported. Furthermore, if desired the member 7 may be loosely passed over the chain 1 so as to facilitate assembly, or if desired the member 7 may be cemented or otherwise rigidly fastened to the chain 1. The housing member 7 is preferably made of as thin glass as is consistent with the requisite strength necessary during the use of the device, and any suitable design such as a series of gold bands or rings 9 may be provided on the lower end of the said housing member 7 to enhance the appearance of the device.

From the foregoing it will be seen that because of the shape of the member 7, it presents a very artistic appearance to the chain and at the same time provides the necessary surface extent to facilitate grasping of the device in a darkened room. Furthermore, the member 7 acts to protect the radium luminescent coating on the member 5 without materially reducing the efficiency of the light that is emitted from the said member, thus the

110

device is capable of being used without actual contact with the coating 5 and with a minimum of light absorption in the protecting housing. Instead of making the member 7 bell shaped it 5 may be of any other suitable shape such as a disc having downwardly converging edges or a hemispherical member such as illustrated in Fig. 2. If the member 10 of Fig. 2 is of rather shallow construction then it may be made of metal or other 10 non-transparent material since its shallowness enables the coated part or marker 5 to be visible through a relatively wide angle. However, it is preferred to make the member 10 out of glass, celluloid or other light transparent material.

15 Fig. 3 shows a further modification wherein the bell shaped member 7 is attached to the chain in a reverse manner, that is with the mouth of the bell facing upwardly. In this case it may be necessary to provide an additional ball or link 11 20 to prevent the member 7 pulling downwardly off the chain.

Fig. 4 shows a still further modification wherein the enclosing terminal is in the form of a ball or sphere 12 substantially completely enclosing 25 the luminous marker 5. In this case of course the member 12 is preferably provided with an opening 13 sufficiently large to permit a proper assembly and a washer or other suitable member 14 may be attached to the member 12 to prevent 30 the said member from sliding off the chain or if desired, the opening 13 may be closed in any other manner for this purpose.

Fig. 5 shows a still further modification of the invention wherein the chain or cord 1 terminates 35 at its lower end in a metal bell shaped member 15 instead of a ball shaped member such as shown in Figs. 1 to 4 inclusive. The member 15 has its outer surface provided with a coating 16 of self-luminous material, such for example as a ra-

dium luminous compound or a compound containing mesothorium. Surrounding the member 15 is an enclosing housing 17 also preferably bell shaped and preferably of glass, celluloid, or other transparent material. The upper end of the housing 17 is provided with a perforation of sufficiently large diameter to pass over the ball links 2, but too small to pass over the terminal 15. In order to prevent the housing 17 from sliding along the chain, an additional large ball member 18 may be attached to the chain above the housing 17. Instead of applying the coating 16 over the entire surface of the member 15, the said coating may be applied in discreet spots around the periphery of the said member 16. This of course also applies to the coating on the member 5 of Figs. 1 to 4 inclusive. That is to say this coating may be applied in either spots, bands or any other design that is found suitable. Preferably, although not necessarily, the member 15 of Fig. 5 conforms in shape to the housing 17.

It will be understood, of course, that in all of the foregoing modifications the members 7, 10 and 12 may be perforated or even made out of fo- 100 raminous material to enable the light from the coating 6 to be emitted directly therethrough.

Various modifications and changes may be made herein without departing from the spirit and scope of the invention.

What is claimed is:

In combination a ball chain terminating in a bell shaped terminal member, a coating of radium luminous material on said terminal member, a transparent glass bell supported directly by said terminal member whereby said coating is visible 110 through said glass bell, said terminal member substantially conforming in shape to the inner face of said glass bell.
